UNITED STATES PATENT OFFICE

FRED J. BURNS, OF SAGINAW, MICHIGAN, ASSIGNOR TO COLUMBIA MILLS, INCORPORATED, OF SAGINAW, MICHIGAN, A CORPORATION OF NEW YORK

VENETIAN BLIND TILT RAIL BRACKET

Application filed March 2, 1931. Serial No. 519,441.

This invention relates to Venetian blinds, the essential elements of which consist of a head rail adapted to be secured at the top of a window or the like, and a depending tilt rail from which a plurality of horizontally disposed thin slats are adjustably supported, and it is the prime object of the invention to provide a demountable tilt rail bracket which can be very readily attached or removed by merely loosening one of the securing screws, after which the tilt rail can be readily shifted into or out of position.

Another object is to design a tilt rail bracket of simple and substantial design, which is economical to manufacture, and which is provided with means for holding the bracket in position regardless of the tightness of the screws.

A still further object is to provide tilt rail brackets which can be easily and quickly detached to permit the removal of the slats and tilt rail as a unit, and which does not necessitate the detaching of the head rail.

The above and other objects will appear 25 as the specification progresses, reference being had to the accompanying drawings in which I have shown the preferred embodiment of my invention, and in which like reference numerals indicate like parts throughout 30 the several views thereof.

In the drawings:

Fig. 1 is a fragmentary front elevation of a Venetian blind embodying my invention.

Fig. 2 is a sectional end view thereof. 25 Fig. 3 is an enlarged transverse sectional view through the tilt rail showing the bracket in position.

Fig. 4 is a plan view of the bracket.

Referring now more particularly to the 40 drawings, the numeral 5 indicates the head rail which is secured in position in the conventional manner, demountable brackets 6 are secured to the head rail by means of screws 7, and a tilt rail 8 is mounted in these brackets, said brackets being formed as clearly shown in Figs. 3 and 4 of the drawings. Pintles 9 are provided in the ends of the tilt rail and are adapted to be mounted in the openings 10 provided in the brackets, to the 45 end that the tilt rail may be pivotally mount-

ed, spaced apart tapes 11 being secured to the tilt rail as shown, and slats 12 are mounted therein, and are tilted by means of the tilt rail in the usual manner.

The head of the bracket is formed as clearly 55 shown in Fig. 4 of the drawings, the rear end being bifurcated, the open slot 13 being of a width to accommodate the body of a screw member 7, a closed slot 14 is provided near the front end of the bracket, and is of a width 60 substantially the same as the slot 13, the inner end however opening into an enlarged section 15, and is of a size to permit the passage of the head of a conventional screw such as used 65 to secure these brackets in position.

Raised sections 16 are provided on opposite sides of the slot intermediate its length, and are formed by pressing the metal when the bracket is being shaped, these sections serving to prevent the bracket working forwardly 70 and becoming detached even if the screws are slightly loose, as the weight of the blind proper is against the underside of the heads of the securing screws.

In practice, the brackets are first spotted 75 on the tilt rail, the screws are then placed in proper position with the head of the front screw ahead of the raised sections 16, now to remove the brackets and tilt rail as a unit, the front screws are turned back (merely one 80 or two turns), the brackets are then slid forwardly (the raised sections 16 passing under the heads of the screws), until the head of the front screw registers with the enlarged end 15 of the slot 14, this forward movement 85 disengages the rear screw from the rear slot, and the bracket can then be dropped down and out of engagement.

The brackets are secured in position in exactly the same manner, it is first raised 90 vertically, the bifurcated end inserted in under the head of the rear screw, the opening 15 registering with the head of the front screw, then with the bracket held against the bottom of the tilt rail, it is moved rearwardly until 95 the screws engage the closed ends of the slots, then by use of a screw driver the screws are turned tight, but in the event this is forgotten no harm will result, as the bracket will still remain in position.

This construction eliminates the use of a screw driver for inserting and removing the rear screw each time the tilt rail is removed, and which is awkward and unhandy due to the slats and other parts of the blind, the front screw, however, is more accessible, and can be readily tightened or loosened as occasion demands.

From the foregoing description it will be obvious that I have perfected a very simple, practical and inexpensive tilt rail bracket for use with Venetian blinds.

What I claim is:

1. In a Venetian blind, in combination with a fixed support, brackets secured thereto and adapted to support a tilt rail, slots provided in the head of said bracket and adapted to accommodate a screw shank, an enlarged section in one of said slots and of a size to permit the passage of a screw head, and a raised portion intermediate the length of the slot to prevent the shifting of said bracket with relation to the screw.

2. In a Venetian blind, the combination with a fixed support, brackets adapted to support a tilt rail, means for securing said brackets in position, slots in said brackets and adapted to accommodate said securing means and to permit removal thereof when said brackets have been shifted to predetermined position, and means intermediate the length of the slots to prevent accidental displacement of said brackets.

In testimony whereof, I hereunto affix my signature.

FRED J. BURNS.
